SCAVENGER ROLL MECHANISM

William Milnarik and John Bradshaw, Yonkers, N. Y., assignors to Alexander Smith & Sons Carpet Company, Yonkers, N. Y., a corporation of New York

Application December 31, 1943, Serial No. 516,346

5 Claims. (Cl. 57—34.5)

This invention relates to machines for spinning textile fibers such as cotton or wool. More particularly, it relates to a spinning frame provided with a new and novel scavenger roll mechanism.

In the usual type of frames for spinning cotton and wool, there is provided a plurality of spinning positions and in each position a yarn end is fed by a pair of yarn-delivery rollers to a rotating twisting head to impart a false twist to the yarn, and thence to drawing rolls from which the yarn is passed through a yarn guide in a guide board to the spinning ring and wound on a bobbin. The corresponding drawing rolls in each position are mounted on a driven shaft extending lengthwise of the frame. The aforementioned frame is also provided with a driven shaft extending lengthwise thereof and positioned beneath the drawing rolls. This shaft, known as the "scavenger roll shaft," is provided with a series of scavenger rolls spaced to correspond to each spinning position, the front portion of the periphery of each scavenger roll being positioned closely adjacent to the path of travel of the yarn from the drawing rolls to the guide, whereby when a yarn end is broken the loose yarn engages the adjacent scavenger roll and is wound thereon, thus preventing the yarn from becoming entangled with adjacent yarn and causing breakage of additional yarn ends. The aforementioned scavenger roll shaft is continuously driven during operation of the frame through appropriate means from one of the drawing roll shafts.

The aforementioned spinning rolls and scavenger roll mechanisms are fully shown and described in United States Patents Nos. 1,774,372, 1,973,534 and 2,024,447.

During operation of spinning frames provided with the aforementioned prior art scavenger roll mechanism, when a yarn end is broken, the loose end or roving engages the adjacent scavenger roll and is wound up thereon. After the operator has spliced the yarn so that it again can be twisted and wound on the bobbin, the waste which has accumulated on the scavenger roll is removed. This is accomplished either by severing the windings, usually with a knife, while on the scavenger roll or by sliding the accumulated waste from the scavenger roll onto the rotating scavenger roll shaft and then cutting the waste so as to remove it from the shaft. Since either of these operations to remove the waste accumulated on the scavenger roll is performed with the aid of a knife, frequent accidents to the operators occur, especially since the removal of the waste must be accomplished while the scavenger roll or the

scavenger roll shaft is rotating. The use of the knife on the scavenger roll also mutilates said roll. When a knife is not used, the operator slides the accumulated waste onto the scavenger roll shaft and pulls it to break it for removal. In any event, the removal of the waste by any of the aforementioned procedures requires a certain amount of time, which interferes with production. When a number of breaks occur at different spinning positions, it becomes necessary to stop the operation of the machine until the broken ends are spliced.

An object of this invention is to provide a scavenger roll mechanism whereby the operator may quickly remove the accumulated waste from the scavenger roll.

A further object of this invention is to provide a scavenger roll mechanism whereby the waste which has accumulated thereon can be removed without the severance thereof.

A still further object of this invention is to provide a scavenger roll mechanism whereby the waste which has accumulated thereon can be effectively removed by sliding the waste therefrom.

Other and additional objects will become apparent from the following description.

The objects, in general, are accomplished by providing a scavenger roll arrangement wherein each scavenger roll is mounted at one end and the other end is free. As will become apparent from the following detailed description, in the preferred form of the invention there is provided a stub shaft which is so mounted that the ends thereof are unsupported and a scavenger roll is secured to each end thereof with one end of the scavenger roll free. The stub shaft is of such length that one of the scavenger rolls carried thereby will be disposed adjacent the path of travel of the yarn from the drawing rolls in one spinning position to catch a broken end of yarn and the other of said scavenger rolls will be similarly disposed to the path of travel of the yarn from the drawing rolls of the next spinning position. A plurality of such stub shafts and scavenger rolls are positioned lengthwise of the frame. Each stub shaft is carried intermediate its ends by a bracket. A rotatably mounted shaft extending lengthwise of the frame is rotatably supported by the brackets. The rotary motion of the shaft is transmitted to each stub shaft by means of a belt cooperating with pulleys carried by the rotating shaft and each stub shaft respectively.

The details of the invention will now be described in connection with the drawing, which

forms a part of this specification and wherein:

Figure 1 is a front elevation of parts of a wool-spinning frame embodying the invention;

Figure 2 is a diagrammatic sectional view; and

Figure 3 is a top plan view of the scavenger mechanism.

Referring now to the drawing, wherein like reference numerals designate like parts, in each spinning position a yarn-delivery roll 10 and a delivery top roll 12 cooperating therewith feed a yarn 14 from the usual source of supply (not shown) to a twisting head 16 where a false twist is introduced in the yarn. The twisting head 16 is carried by a bracket 20 suitably mounted in the frame and is rotated by a belt 18 driven in the usual manner by means, not shown. Since the details of construction of the twisting head 16 are known and form no part of this invention, further description thereof is unnecessary.

The yarn 14 passes from the twisting head 16 to the drawing rolls 22 and 24, which are preferably fluted. A presser roll 26 cooperates with the drawing rolls 22 and 24. The rolls 22, 24 and 26 are preferably weighted. Since the details of construction of the weighting mechanism are well known, further description thereof is deemed unnecessary. From the drawing rolls, the yarn 14 passes through a guide 30 of a guide board 32, carried on the frame at 34 and hinged at 36 to a spinning ring 40, and wound on bobbins 42. The drawing rolls 22 are mounted on a shaft 44, which extends lengthwise of the machine and is driven from a suitable source of power (not shown). The rotary movement of the shaft 44 is transmitted to a shaft 46, which also extends lengthwise of the machine and carries the drawing rolls 24, by means of a gear 48 on the shaft 44, an idler gear 50 appropriately mounted in the frame and a gear 52 carried on the shaft 46. The aforementioned description of the spinning frame are details of construction of a standard wool-spinning frame.

The scavenger roll mechanism which constitutes the instant invention will now be described. As shown in Figure 1 of the drawing, there is provided a plurality of stub shafts 60, each of which is rotatably mounted intermediate its ends in the arms 62 of a bifurcated bracket 64, there being one bracket for each stub shaft. Each bracket is secured to the frame of the machine by bolts 66 and disposes the stub shaft carried thereby beneath the drawing rolls and above the guide 30. On each unsupported end of each stub shaft 60 there is rigidly secured a scavenger roll 68, and, as shown in Figure 3, the outside end of each scavenger roll is free. Each stub shaft 60 is of such length that one of the scavenger rolls 68 carried thereby will be disposed adjacent the path of travel of the yarn from the drawing rolls in one spinning position so that when the yarn or roving breaks it will be engaged and wound up on said scavenger roll and the other scavenger roll carried thereby will be similarly disposed to the path of travel of the yarn from the drawing rolls in the next adjacent spinning position. Each stub shaft 60 is provided with a pulley 70 which is driven by a belt 72, which in turn is driven by a pulley 74 secured to a shaft 76 extending lengthwise of the machine and rotatably carried by the brackets 64. Adjacent one end thereof, the shaft 76 is provided with a gear 78 which is driven by the gear 48 through the gear 50. The portions of the shaft 76 between the brackets 64 may be enclosed with a protective covering.

Each scavenger roll 68 is tapered toward the free end thereof so that the waste accumulated thereon may be efficiently and effectively removed by merely sliding or rolling it toward and off the smaller free end. Due to the manner of mounting the scavenger rolls, the waste, after being rolled or slid over the free end, is completely removed from the spinning frame without any additional operation. Though it is preferred that the stub shaft does not project from the free end of the scavenger roll, nevertheless it may project slightly if it does not interfere with the removal of the waste. Each scavenger roll 68 is also provided with a felt covering whereby it will more effectively engage any broken yarn.

Herein the term "yarn" is used generically to cover a yarn, strand, or roving formed of any textile material, such as wool, cotton, rayon, nylon, spun rayon, etc.

In operation, when a yarn in any spinning position breaks, the yarn upon issuing from the drawing rolls will be engaged by the scavenger roll disposed therebeneath and will be wound thereon until removed by the operator. In usual operation, after the broken end has been spliced and spinning at that position resumed, the operator rolls or slides the waste which has accumulated on the scavenger roll toward the free end thereof. This rolling or sliding operation is continued until the waste is free of the scavenger roll. It will be noted that the sliding or rolling of the waste removes it from the scavenger roll without any other operation. There is no need for severing the waste on the scavenger roll or at any time. There is no shaft on which the waste is removed from the scavenger roll and from which it must be subsequently removed. The operation is quickly and effectively accomplished with no danger of injury to the operator.

The instant scavenger roll arrangement is relatively cheap and may be applied to spinning machines of various types. It provides an effective mechanism for quickly removing the waste which has accumulated on a scavenger roll with a minimum danger of injury to the operator. The removal of the waste from the scavenger roll by the operator can be performed in a very short interval of time, with the result that the work load on the operator is reduced. Further, because of the quick removal of the waste by the operator, when a number of breaks occur at different spinning positions, the operation of the frame need not be stopped in order to quickly remove the waste nor to make the necessary splices and remove the waste.

Since it is obvious that many changes and modifications can be made in the above-described details without departing from the nature and spirit of the invention, it is to be understood that the invention is not to be limited thereto except as set forth in the appended claims.

We claim:

1. In a yarn-spinning frame having a plurality of spaced spinning positions and wherein each spinning position includes a set of drawing rolls, a rotatable stub shaft having at least one end thereof unsupported and disposed beneath the drawing rolls, a scavenger roll on the unsupported end of said stub shaft whereby said scavenger roll will be disposed beneath said drawing rolls in position to catch a broken end of yarn, and means to continuously rotate said stub shaft during operation of the frame.

2. In a yarn-spinning frame having a plu-

rality of spaced spinning positions and wherein each spinning position includes a set of drawing rolls, a stub shaft beneath the drawing rolls, means rotatably supporting said stub shaft intermediate the ends thereof whereby the ends of said stub shaft are unsupported, a scavenger roll secured on each end of said stub shaft, said stub shaft being of a length to disposed one of said scavenger rolls adjacent the path of travel of the yarn from the drawing rolls in one spinning position to catch a broken end of the yarn and the other of said scavenger rolls similarly to the path of travel of the yarn from the drawing rolls of the next spinning position, and means to continuously rotate said stub shaft during operation of the frame.

3. In a yarn-spinning frame having a plurality of spaced spinning positions and wherein each spinning position includes a set of drawing rolls, a bracket on said frame, a stub shaft rotatably mounted intermediate the ends thereof in said bracket whereby the ends of said stub shaft are unsupported, said bracket disposing said stub shaft beneath the drawing rolls, a scavenger roll secured on each end of said stub shaft, said stub shaft being of a length to dispose one of said scavenger rolls adjacent the path of travel of the yarn from the drawing rolls in one spinning position to catch a broken end of the yarn and the other of said scavenger rolls similarly to the path of travel of the yarn from the drawing rolls of the next spinning position, a shaft extending lengthwise of the frame, means to continuously rotate said shaft during operation of the frame, and means to drive said stub shaft from said shaft.

4. In a yarn-spinning frame having a plurality of spaced spinning positions and wherein each spinning position includes a set of drawing rolls, a plurality of spaced brackets on said frame, a stub shaft rotatably mounted intermediate its ends in each of said brackets whereby

5 the ends of said stub shaft are unsupported, each of said brackets disposing the stub shaft carried thereby beneath the drawing rolls, a scavenger roll secured on each end of each of said stub shafts, each stub shaft being of a length to dispose one of said scavenger rolls adjacent the path of travel of the yarn from the drawing rolls in one spinning position to catch a broken end of the yarn and the other of said scavenger rolls similarly to the path of travel of the yarn from the drawing rolls of the next spinning position, a shaft extending lengthwise of the frame and rotatably mounted in said brackets, means to drive said shaft during operation of the frame, and means to drive said stub shafts from said shaft.

20 5. In a yarn-spinning frame having a plurality of spaced spinning positions and wherein each spinning position includes a set of drawing rolls, a plurality of spaced brackets on said frame, a stub shaft rotatably mounted intermediate its ends in each of said brackets whereby the ends of said stub shaft are unsupported, each of said brackets disposing the stub shaft carried thereby beneath the drawing rolls, a scavenger roll on each end of said stub shaft, said stub shaft being of a length to dispose one of said scavenger rolls adjacent the path of travel of the yarn from the drawing rolls in one spinning position to catch a broken end of the yarn and the other of said scavenger rolls similarly to the path of travel of the yarn from the drawing rolls of the next spinning position, a shaft extending lengthwise of the frame and rotatably mounted in said brackets, means driven by the driving means for the drawing rolls to continuously drive said shaft during operation of the frame, and means to transmit the rotary movement of said shaft to each of said stub shafts.
